UNITED STATES PATENT OFFICE.

CHARLES K. DUNLAP, OF HARTSVILLE, SOUTH CAROLINA, ASSIGNOR TO SONOCO PRODUCTS COMPANY, OF HARTSVILLE, SOUTH CAROLINA, A CORPORATION OF SOUTH CAROLINA.

PAPER TUBE.

Application filed March 31, 1926. Serial No. 98,885.

This invention relates to paper tubes and to a method of surfacing such tubes for use on knitting machines, creeling machines and similar devices.

5 The principal objects of this invention are: to provide a paper tube having a thread or yarn receiving surface which has an increased ability to resist slippage of thread or yarn wound upon it, to provide a paper tube 10 having a surface truly cylindrical in cross section, or a true surface of revolution; and to accomplish these aforesaid results in a satisfactory and inexpensive manner by means of a novel method. Other objects of 15 this invention will be apparent from the following description taken in connection with the accompanying drawings, in which:

Fig. 1 shows the essential elements of a machine which may be used to carry out the 20 process of treating paper tubes in accordance with the present invention;

Fig. 2 is an end elevation of a tube before surfacing;

Fig. 3 is an end elevation of a tube after 25 surfacing to show the manner in which part of the outer layers of paper are ground away to produce a velvety surface and a circular periphery;

Fig. 4 is a side view of a conical tube 30 surfaced as shown in Fig. 3; and

Fig. 5 is a side view of a cylindrical tube 35 surfaced as shown in Fig. 3.

In the manufacture of tubes to hold yarn or thread for knitting and creeling machines, 40 paper has proven to be the cheapest and most satisfactory material. But in the use of paper tubes various difficulties are encountered and some of these difficulties will now be considered in order that a clearer understanding may be obtained of the merits of the present invention.

One of the principal difficulties encountered in the use of paper tubes is the slippage of thread or yarn along the surface of the 45 tube. This slippage is particularly likely to occur when hard fibered yarn or thread such as silk or linen is wound on the tubes. When the tube is cone shaped the slippage is more common but when it is cylindrical 50 slippage will still occur if the tube is tapped endwise or the thread is pulled toward one end of the tube in feeding. Heretofore, slippage on both conical and cylindrical

types of tubes has been prevented by covering the tube with a layer of cotton yarn or 55 by gluing a thin sheet of chamois skin or other suitable material on the surface of the tube. Both expedients, and particularly the latter, have proven effective for preventing slippage but have been found to be too expensive for general use. Another expedient has been that of making the tube of a softer paper so that when the paper was wound upon itself in forming the tube the outer 60 surface was of the desired roughened velvety 65 texture. This expedient also has been found unsatisfactory because soft paper does not produce a tube of requisite strength, a hard paper being needed for this.

Another difficulty encountered in the use 70 of paper tubes is the jumping effect given the thread while it is being wound or unwound from the tube due to the eccentricity of the tubes. This eccentricity is caused by the method of making the tube which consists of winding the paper upon itself in 75 layers. The end of the paper as thus wound forms a bump on the outer surface of the tube. An expedient adopted to lessen this difficulty has been that of feathering the 80 outer edge of the paper but this was not entirely effective for some eccentricity still remained after feathering.

And yet another difficulty encountered is the unequal yardage of thread in a given 85 number of turns on various tubes due to variations in outer circumferences. This is caused by a lack of uniformity in the gauge of the paper stock used in forming the tubes. For instance, 8 point paper will vary 90 between 7 and 9 points in the grades of paper used in tube making so one tube made of a certain number of turns of so called 8 point paper which ran 7 point would be considerably smaller than one made of the same 95 number of turns which ran 9 point.

According to the present invention all of these difficulties are eliminated very effectively and very cheaply by the simple method of grinding or abrading and brushing the surface of the tubes. This produces tubes that are of uniform diameter, which insures that all tubes will receive the same yardage of thread for a given number of turns; that have true surfaces of revolution, 105 which insures that there will be no jumping.

or jerking to break or kink the thread as it is wound on or off the tubes at high speed; and that have a thread receiving surface similar in texture to chamois skin, which insures that smooth hard thread wound on the tubes will not slip off easily.

Referring to the drawings in which an embodiment of this invention is illustrated, Figure 1 shows the essential elements of one form of mechanism for carrying out the operations according to this invention, it being understood that the machine itself forms no part of the present invention. Here reference character 12 designates a base or stand having a pedestal 13. This pedestal has a bearing ring 14 in which a head 15 is mounted for intermittent rotation. Spaced at equal points about the circumference of this rotatable head are planetary rotatable spindles 16 which are adapted to carry tubes 17 to be ground. Beyond the periphery of the head and with the same circumferential spacing as the spindles 16 are fixed rotatable spindles 18, 19 and 20 carrying a grinding wheel 21, a stiff brush 22, and a cut off disc 23, respectively. The head 15 and shafts 16, 18, 19 and 20 are given their proper movement in any suitable manner. The mechanism for imparting this movement is not shown as any suitable mechanism may be used. The device shown has four spindles 16 mounted in the head so one spindle will be in idle position for feeding and removing tubes therefrom. A tube is inserted at position marked A, ground at position marked B, brushed at position marked C, cut off at position D and removed at position A.

Figure 2 shows in end view a tube as manufactured by winding and gluing a strip of paper upon itself. This leaves an outer end M upstanding to cause jumping of the thread and an inner end N to cause an eccentric bulge in the tube when it is pushed tightly upon a circular shaft. Figure 3 shows the same tube after having its outer surface ground and brushed to a true circular shape in cross section while the tube was mounted upon a circular shaft similar to the shaft upon which the tube is mounted for winding and unwinding thread.

Figure 4 shows a winding tube, in this case a cone, which has been surfaced according to the present invention. This illustrates as well as may be illustrated in a drawing the velvety surface given the spool.

Figure 5 illustrates a cylindrical tube having a true cylindrical velvety surface produced according to the present invention.

While the description has been directed to some extent to tubes for winding yarn it is to be understood that the invention is not thus limited but includes tubes for other purposes; and the manner of surfacing the tubes is not limited to the exact method de-

scribed but may be accomplished in other ways; all such variations to fall within the scope of the appended claims.

It will also be understood that the tubes or cores may have widely different shapes 70 and dimensions.

In the appended claims the tubes are said to be subjected to an "abrading" action and to have "velvety" surfaces or surfaces offering increased resistance to yarn or thread 75 slippage because of the presence of a "nap" thereon. The words chosen are thought to be apt but it will be understood that they are words of general description rather than words of limitation and that the method 80 and product might be otherwise described.

Having thus described my invention, what is claimed as new and desired to be secured by Letters Patent is:

1. The method of treating a paper tube 85 preparatory to its use in the textile industry as a core for a thread cop or winding, consisting in subjecting a surface of the same to an abrading action, whereby the ability of such surface to retain thread or yarn thereon 90 without slippage is increased.

2. The method of treating a paper tube preparatory to its use in the textile industry as a core for a thread cop or winding, consisting in subjecting a surface of the same to an abrading action whereby a nap is raised thereon which increases the ability of such surface to retain yarn or thread thereon without slippage.

3. The method of treating a paper tube preparatory to its use in the textile industry as a core for a thread cop or winding, consisting in subjecting a surface of the same to an abrading action, and in subsequently brushing the same whereby a thread retaining surface having increased ability to retain thread or yarn without slippage is provided, which surface is free of loose paper particles.

4. The method of preparing a paper tube 110 for use as a core for thread cops or windings in the textile industry, having increased ability to retain yarn without slippage, which consists in subjecting the outer surface of the tube to an abrading action and thereby raising a thread retaining nap on 115 such surface, and brushing the surface after the grinding operation to remove loose particles and comb out the nap.

5. The method of fabricating paper tubes 120 for use as cores for thread cops or windings in the textile industry consisting in winding sheet paper stock into the form of a tube, securing the convolutions together by an adhesive, and abrading the outer surface of the tube whereby the ability of such surface to retain thread or yarn without slippage is increased.

6. The method of fabricating paper articles for use as cores for thread cops or windings in the textile industry, consisting

- in winding paper sheet stock upon itself to form a tube, securing the convolutions together with an adhesive, subjecting the outer surface of the tube to an abrading action 5 to produce a surface having increased ability to retain yarn without slippage, and brushing the surface after the grinding operation to remove loose particles and comb out the nap.
- 10 7. The method of fabricating paper tubes for use as cores for thread cops or windings in the textile industry, consisting in subjecting the outer surface of such tube to the action of an abrading device, to raise 15 a nap thereon which tends to prevent yarn slippage and at the same time to make such surface a true surface of revolution.
8. The method of fabricating paper tubes for use as cores for thread cops or windings in the textile industry, consisting in 20 winding sheet paper stock into the form of a tube, securing the convolutions together by means of an adhesive, abrading the surface of the tube to produce an improved 25 slip resisting surface which is a true surface of revolution centered on the axis of the tube, and brushing the surface of the tube, as set forth.
9. The method of fabricating paper articles for use as cores for thread cops and windings in the textile industry, consisting in 30 winding paper sheet stock to form a tube, securing the convolutions together by an adhesive, subjecting the outer surface of the 35 tube to the action of an abrading device in such manner as to provide an improved slip resisting surface and to cause the same to become a true surface of revolution.
10. The method of preparing a paper tube 40 for use as a core for thread cops or windings in the textile industry which consists in abrading the outer surface of the tube and brushing the same, the grinding being effected while the tube is rotating about a 45 fixed axis, with the active surface of the grinding device remaining in fixed position relative to said axis during the grinding operation, whereby the tube is given a surface truly circular in cross section and centered on said axis and is given at the same 50 time an improved surface which has increased ability to retain thread or yarn thereon without slippage.
11. As an article of manufacture, a paper core of the class described characterized by 55 a thread receiving surface of the form of a true surface of revolution without surface irregularities, and of a soft velvety texture due to projecting fibers of the material of the core. 60
12. As an article of manufacture, a paper core of the class described having a portion treated by abrading means to provide an improved thread receiving surface of uniform character thruout which offers increased resistance to thread slippage. 65
13. As an article of manufacture, a paper core of the class described having a thread retaining nap consisting of projecting fibers of the material of the tube.
14. As an article of manufacture, a core comprising sheet paper stock wound upon itself to form a tube, said tube having a thread retaining nap on its outer surface consisting of projecting fibers of the material of the tube.
15. As an article of manufacture, a tube for use as a core for thread cops or windings in the textile industry, said tube comprising a spirally wound sheet of paper, the 80 surface of which is a true surface of revolution and which surface has a thread retaining nap consisting of projecting fibers of the material of the tube.
16. A paper tube for use as a core for 85 thread cops or windings in the textile industry comprising a hollow core of hard paper fiber, the outer surface of the core being truly circular in cross section and having a thread retaining nap consisting of 90 filaments of paper fiber extending outwardly.
17. A paper core for use in the textile industry having a surface truly circular in cross section and a thread retaining nap, the material of the core being homogeneous 95 throughout and the nap comprising outwardly extending filaments of the same material.
- In testimony whereof I hereunto affix my signature.

CHARLES K. DUNLAP.
